UNITED STATES PATENT OFFICE

EVALD ANDERSON, OF ALHAMBRA, CALIFORNIA, ASSIGNOR TO INTERNATIONAL PRECIPITATION COMPANY, OF LOS ANGELES, CALIFORNIA. A CORPORATION OF CALIFORNIA

ELECTRODE FOR ELECTRICAL PRECIPITATION APPARATUS

Application filed October 8, 1929. Serial No. 398,486.

This invention relates to apparatus for electrical precipitation of suspended material from gases, and particularly to the construction of collecting electrodes for use in such apparatus. This application relates to subject-matter originally disclosed in my application, Ser. No. 154,131, filed December 11, 1926, for "Apparatus for electrical precipitation of suspended material from gases." It has been found advantageous in certain cases of electrical precipitation to use collecting electrodes of semi-conducting material, for example, concrete or cement material as set forth in my United States Patent No. 1,541,677 issued June 9, 1925. Such semi-conducting electrodes have heretofore ordinarily been made in the form of plates or slabs containing embedded metallic reinforcing and conducting members. Each collecting electrode has been made either as a single integral slab or plate of this type or as a plurality of sections mounted and connected together in suitable manner. In practice it is generally necessary to make the electrodes of considerable height and width so that an electrode formed as a single integral plate is necessarily of relatively great weight and therefore difficult to handle. Also, in order to permit mounting of such plates within the precipitating chambers and provide for subsequent removal thereof for repair or replacement, it has been customary to provide removable covers for the precipitating chambers and to provide a suitable overhead beam or rail extending across above these covers at a suitable height to permit the collecting electrodes to be suspended from this beam and moved over the tops of the precipitators to the desired position and then lowered into place in the chamber. This, however, requires a considerable amount of extra space or head room above the tops of the precipitators. For example, for handling concrete collecting electrode plates of 12 feet in height, an equal height of clear space is required

above the tops of the precipitating chambers. This space is sometimes not available and in many instances the space required for this purpose could be utilized to good advantage for other purposes.

A further objection to these integral plate collecting electrodes is that, due to the relatively small thickness thereof, there is a tendency for them to buckle or deform under certain conditions of operation, particularly where the gases to be treated are at high temperature or subject to sudden fluctuations in temperature. Such deformations of the electrodes may lead to serious difficulty due to irregularity in the space of different portions of the collecting electrode from the opposing discharge electrodes, which interferes with satisfactory operation of the precipitator.

The use of collecting electrode plates made up of relatively small sections or slabs has therefore been proposed, both as a means of lessening the tendency to buckling and deformation and in order to reduce the head room required above the top of the precipitator chambers for moving these sections and from their positions in the installation. Considerable difficulty, however, has been experienced in supporting and connecting together these plate sections, and furthermore the weight of the complete electrode is as great in this case as though the same were formed in one piece.

An important object of the present invention is to provide a type of semi-conducting collecting electrode construction which overcomes the above mentioned objections, that is, a construction in which only a relatively small head room or free space is required above the tops of the collecting electrode chambers for moving the elements of the collecting electrodes to and from their positions in the installation, in which the elements to be handled are of relatively small size and weight and may be easily assembled in place to form a completed electrode which

is of considerably less weight than the plates heretofore used, and in which there is little or no opportunity for warping or buckling, so that all portions of the collecting electrode are maintained at uniform spacing from the opposing discharge electrodes.

The collecting electrode of this invention comprises essentially a plurality of closely spaced vertically extending elements of semi-conducting material, each of which is preferably of circular cross section such as a long cylindrical rod-shaped element of suitable diameter. Each of said elements is provided with a metallic supporting member extending centrally thereof and serving not only to support such element in proper position but also to conduct electric current throughout the length thereof. A separate metallic supporting member is provided for each element, and the supporting members for all the elements of each collecting electrode are preferably secured at their upper ends to a common supporting member. The elements of each collecting electrode are placed sufficiently close together so as to approximate the effect of a continuous surface, so that if a row of suitably spaced discharge electrode elements is placed at the proper distance from the row of collecting electrode elements there will be substantially the same amount of electric discharge and hence substantially the same amount of electrical precipitating action as though a plate collecting electrode having a continuous plane surface were used.

Each of these vertically extending collecting electrode elements is also preferably formed of a plurality of superposed sections so as to reduce or entirely eliminate the tendency to warping or buckling thereof in a vertical plane. These sections may either be secured to the central supporting and conducting member, or they may be loosely strung thereon, and the lowermost section supported upon said member in any suitable manner. Since the elements are hung separately from one another there is of course substantially no tendency to buckling or deformation of the assembled collecting electrode in a horizontal plane, and all parts of the electrode are, therefore, maintained substantially in alignment with the intended plane or surface and at the proper distance from the discharge electrodes.

The accompanying drawings illustrate embodiments of my invention and referring thereto:

Fig. 1 is a vertical section of a portion of the electrical precipitating apparatus showing a collecting electrode according to my invention mounted therein.

Fig. 2 is a transverse section through two adjacent collecting electrodes, taken on line 2-2 in Fig. 3.

Fig. 3 is a horizontal section on line 3-3 in Fig. 2.

Fig. 4 is a horizontal section of a modified form of electrode construction according to this invention.

Fig. 5 is a horizontal section of another modification.

Fig. 6 is a vertical section of a modified construction of one of the electrode elements.

The precipitating apparatus shown in Fig. 1 comprises suitable housing means 1 enclosing a precipitating chamber 2 through which the gases to be treated are passed, said housing being also provided with suitable means such as a hopper indicated in part at 3, for receiving the suspending material separated from the gases. Suitable collecting electrodes 4 and discharge electrodes 5 are mounted within said chamber.

The discharge electrodes comprise rows of suitably spaced elongated members of small diameter formed of suitable conducting material such as metal, for example, iron wires or small diameter rods, mounted on suitable supporting frames 6 carried by beams 7 which rest on insulating supports 8.

Each collecting electrode is shown as comprising a plurality of elements 9 of circular cross section, formed of semi-conducting material such as concrete, cement, terra cotta, etc., and extending vertically in closely spaced arrangement and substantially in a single vertical plane so as to provide a curtain-like electrode structure formed by a row of these rod-shaped elements. The elements of each electrode curtain are sufficiently close together to approximate electrically the effect of a smooth surfaced plate. Each element is preferably also made up of a plurality of sections 11 mounted contiguously one above another. A metallic reinforcing and conducting member 12 extends centrally throughout the length of each element or of all the sections thereof, and said elements or sections are supported in any suitable manner on said supporting members. For example, as shown, each supporting member may have an enlargement 13 at its lower end providing a shoulder 14 and the lower end of each collecting electrode element or of the lowermost section thereof may be recessed as at 15 so as to pass over this enlargement and rest upon said shoulder.

The remaining sections may simply be strung on the central rod and rest upon one another. The rod-shaped collecting elements, or the sections thereof, may be made in any suitable manner, as by spinning or casting, with an axial hole of sufficient size to receive the supporting and conducting rod. In order to prevent direct exposure of the central metallic supporting members 12 to the electrical and thus avoid passage of electrical discharge directly between the discharge electrodes and these members, I prefer to provide adjacent sections 11 with interlocking pin and recessed portions indicated at 19 and 130

20, overlapping one another. Any suitable means may be provided for supporting all of the elements of each collecting electrode. Such means is shown, however, as comprising a common supporting member such as a channel 16 supported at its ends on the housing in any suitable manner, the upper ends of the supporting rods 12 for the several elements being removably supported on said channel as by means of nuts shown at 17. Said supporting rods are preferably secured to the common support 16 in such manner as to hang freely, so that they will be maintained in proper vertical position by their own weight. 5 It will be understood that the several curtain-like collecting electrodes thus constituted are hung in parallel arrangement within the precipitating chamber 2, while the rows of discharge electrodes 5 are mounted midway between each pair of collecting electrodes, as 10 shown for example in Fig. 3. The top of the precipitating chamber is preferably formed as a removable cover plate 18, which may be removed to permit easy access thereto, for 15 mounting and removal of the collecting electrodes, which may either be handled bodily, or the individual elements or sections may be handled separately and assembled in position. This latter method of assembly is particularly 20 advantageous, as the individual parts handled are small and do not require much free space above the top of the precipitator.

As shown in Fig. 4 the collecting electrode elements 9 which may, for example, be of the 25 same construction as above described may be disposed in circular arrangement about a central discharge electrode 5 so as to form a collecting electrode of a shape resembling the well known pipe or tube electrode.

40 Another modification is shown in Fig. 5 in which the rod-shaped semi-conducting collecting electrode elements 9 are arranged in rows extending in two perpendicular directions so as to form square flues or spaces 21 45 therebetween, the discharge electrodes 5 being in this case disposed centrally of said flues.

In some cases, in order to provide for more 50 uniform electrical contact of all portions of the elements or sections of semi-conducting material with the supporting and conducting members extending centrally therethrough, I may provide each section 11' of each element 9' with a metallic sleeve or pipe 22 as shown 55 in Fig. 6, said sleeve being preferably molded or embedded in the concrete or other semi-conducting material and fitting more or less closely on the metallic supporting rod 12'.

It is to be understood that in each of the 60 above forms of the invention means will be provided for connecting the discharge electrodes to a source of high potential electric current. For example, the discharge electrode system may be connected to suitable 65 rectifying apparatus for supplying the elec-

trical precipitator with rectified alternating current, the collecting electrodes being connected to the other side of said rectifying apparatus and being preferably also grounded.

In the operation of the apparatus a suitable potential difference, say 50,000 to 100,000 volts depending on the spacing between the discharge and collecting electrodes and the nature of the gas to be treated, is maintained between said electrodes, and the gas is passed through the passages between the collecting electrodes and the discharge electrodes. With electrodes as shown in Fig. 1, the gas may pass either horizontally or vertically in a direction parallel to the plane of the electrode curtains, but the particular apparatus shown is intended for horizontal flow, for example in the direction by the arrows in said figure. With electrodes of the form shown in Figs. 4 and 5, on the other hand, the direction of gas flow is vertical, or longitudinally of the passages between the electrode curtains. The high potential difference maintained between said electrodes produces electrical discharge from the discharge electrodes and consequent precipitation of suspended material by electrical action on the electrodes and particularly upon the collecting electrodes. The particles so precipitated may either fall from the electrodes by gravity, or 90 may be dislodged therefrom by any suitable means, and are collected in the hopper or other collecting means at the bottom of the precipitating chamber. The above described apparatus may also be used for agglomeration of suspended matter in the gases by 95 maintaining either a unidirectional or alternating high potential difference therebetween.

I claim:

1. A collecting electrode for electrical precipitating apparatus comprising a common horizontal supporting member, a plurality of vertically extending metallic supporting members removably secured to said horizontal supporting member and depending therefrom, and individual cylindrical elements of semi-conducting material surrounding and supported by the respective vertical supporting members, each of said cylindrical elements comprising a plurality of directly contiguous sections one above another and completely enclosing the corresponding metallic member throughout the height of said element.

2. A collecting electrode for electrical precipitating apparatus comprising a plurality of separate closely spaced vertically extending elements of semi-conducting material each having a single metallic supporting and conducting member extending centrally throughout the height thereof, and each of said elements comprising a plurality of directly contiguous sections one above another and completely enclosing the corresponding

metallic member throughout the height of said element.

3. In a collecting electrode for electrical precipitating apparatus, a vertically extending metallic supporting and conducting member and a plurality of directly contiguous cylindrical sections of semi-conducting material mounted one above another and completely surrounding said metallic member and supported thereby.

In testimony whereof I have hereunto subscribed my name this 27th day of September, 1929.
